UNITED STATES PATENT OFFICE

122,784

DESIGN FOR A CHRISTMAS TREE ORNAMENT OR SIMILAR ARTICLE OF MANUFACTURE

Gilbert D. Snyder, Belle Harbor, N. Y., assignor to Parfumerie De Raymond, New York, N. Y.

Application August 3, 1940, Serial No. 94,184

Term of patent 7 years

To all whom it may concern:

Be it known that I, Gilbert D. Snyder, a citizen of the United States of America, residing at Belle Harbor, in the county of Queens and State of New York, have invented a new, original, and ornamental Design for a Christmas Tree Ornament or Similar Article of Manufacture, of which the following is a specification, reference being had to the accompanying drawing, forming a part thereof, and showing a perspective front view of the Christmas tree ornament embodying my design.

I claim:

The ornamental design for a Christmas tree ornament or similar article of manufacture.

GILBERT D. SNYDER.
